UNITED STATES PATENT OFFICE.

JEAN B. BOISSELOT, OF NEW YORK, N. Y., ASSIGNOR TO EDUARD VAN DAM, OF NEW YORK, N. Y.

IGNITION-PLUG FOR EXPLOSIVE-MOTORS.

SPECIFICATION forming part of Letters Patent No. 692,975, dated February 11, 1902.

Original application filed October 11, 1900, Serial No. 32,693. Divided and this application filed January 2, 1901. Serial No. 41,791. (No model.)

To all whom it may concern:

Be it known that I, JEAN BAPTISTE BOISSELOT, a citizen of France, residing at No. 402 East One Hundred and Sixteenth street, New York city, in the county of New York and State of New York, have invented certain new and useful Improvements in Ignition-Plugs for Explosive-Motors, of which the following is a specification, reference being had therein to the accompanying drawings.

This invention relates generally to explosive-motors using any of the well-known hydrocarbons and in which the explosive mixture is ignited by an electric spark and adapted for use in stationary and other motors and automobiles.

It more particularly relates to the sparking or ignition plug, providing a holder for the plug that is guarded against leakage by shocks or blows and which is constructed for ready assembling and dismantling.

A practical embodiment of the improvements is illustrated in the accompanying drawings, in which—

Figure 1 is a sectional elevation thereof with a portion of the motor-cylinder to which it is connected. Fig. 2 is a similar view of a modification detached from the motor-cylinder. Fig. 3 is a plan view of the ignition-plug, and Fig. 4 is a central vertical section of the plug as shown in Fig. 1.

The motor with which the improved ignition-plug N is used may be of any suitable form—such, for instance, as that illustrated and described in my pending application, Serial No. 32,693, filed October 11, 1900, of which this is a division, the motor being represented therein by a portion of the water-jacketed motor-cylinder B.

The ignition-plug consists of a cup-shaped base 24, screwed into the motor-cylinder B and carrying one of the sparking terminals 1 in circuit with the motor-framework. It carries a porcelain rod 2, secured in position by

a nut 3 and through which the other spark- 45 ing terminal passes from a metallic piece 4, which in turn is borne upon by the head of the binding-post 5, that is mounted loosely in the insulated head 6 of the plug. The cup-shaped base 24 carries a sleeve 7, threaded 50 thereto, and the sleeve carries the head 6, between which and the binding-post head a suitable spring 8 is interposed. The sleeve 7 may be closed, as in Fig. 1, or the sleeve may be perforated, as in Fig. 2, for admission of currents of air to the interior.

By reason of the construction described and shown the parts of the ignition-plug are thus readily taken apart, while the independence of the insulating-rod 2 to the binding-post 5 60 and the manner of supporting said rod 2 prevent the accidental rupture of the latter.

The binding-post 5 will be in circuit with any proper form of sparking regulator or circuit-breaker, such as that shown in my said 65 pending application.

What I herein claim is—

1. In a motor, an igniting-plug provided with an insulated terminal holder and a yieldingly-mounted binding-post in contact with 70 the terminal of said holder, as described.

2. In a motor, an ignition-plug provided with an insulated terminal holder, a yieldingly-mounted binding-post in contact with the terminal of said holder, and a surround- 75 ing sleeve, as described.

3. In a motor, an ignition-plug provided with a base, an insulated terminal holder mounted in said base, a removable sleeve carried by said base, an insulated head carried 80 by the sleeve and a yielding binding-post mounted in said head, as described.

In testimony whereof I affix my signature in presence of two witnesses.

JEAN B. BOISSELOT.
